Patented Oct. 14, 1924.

UNITED STATES PATENT OFFICE.

NORMAN HOWARD CAUFIELD, OF VICTORIA, BRITISH COLUMBIA, CANADA.

STOOKING-MACHINE ELEVATOR.

Application filed September 23, 1921. Serial No. 502,711.

To all whom it may concern:

Be it known that I, NORMAN HOWARD CAUFIELD, a subject of the King of Great Britain, and a resident of the city of Victoria, in the Province of British Columbia, Canada, have invented certain new and useful Improvements in Stooking-Machine Elevators, of which the following is a specification.

10 My invention relates to improvements in stooking machine elevators, and the object of my invention is to provide a device of this nature by means of which the sheaves may be transferred from the binder to the 15 stooker automatically and in a simple, practical, and highly efficient manner.

I attain this object by the construction illustrated in the accompanying drawings in which—

20 Fig. 1 is a side view of the elevator.

Fig. 2 is a plan view.

Fig. 3 is a detail view of the elevator shaft arm connection.

Similar figures of reference indicate similar parts throughout the several views.

In the drawings 1 indicates the frame of a stooking machine and 2 the basket, which is represented in the normal horizontal position, that is, the sheaf-receiving position, 30 while 3 indicates a portion of the binder elevator platform and 4 the kicker shaft associated with the binding device.

The stooker elevator consists of a frame having two side bars 5 and 6 rigidly connected at one end to the binder platform 3, as at 7, while their opposite ends are formed as bearings 8 and 9 arranged to lie adjacent the side of the stooker frame, as shown, through which bearings extends movably a 40 shaft 10, which shaft is mounted in bearings 11 and 12 secured to the stooker frame, from which it will be seen that the side bars 5 and 6 are firmly supported between the stooker and the binder, and as the width 45 between the bars is less than the length of a sheaf, the bars form a frame or platform on which the sheaves may be deposited, as hereinafter described. Braces 13 and 14 are provided for the side bars, between which 50 braces extends a bar 15, and this bar 15 is preferably supported intermediate its length by a vertical bar 16 extending between the bar 15 and the outer end of a horizontal bar 17 the opposite end of which is formed as a 55 boss 18 through which shaft 10 extends.

Secured to the shaft 10 at spaced inter-

vals and within the frame formed by the bars 5 and 6 are short arms 19, 20, and 21 to the ends of which are pivotally connected, as at 22, longer arms 23, 24 and 25 the outer ends of which are curved upwardly, as at 26, and rest normally on the bar 15, and to each of these arms 23, 24 and 25 are secured intermediate their length vertical bars 27, 28, and 29 respectively. The position of the bars 27, 28, and 29 with relation to the ends of their respective arms, and the length of the arms themselves, is such that when in normal position, a sheaf deposited on the side bars 5 and 6 will lie directly over the three arms 23, 24, and 25 and between the bars 27, 28 and 29 and the ends of the arms.

Each arm 23, 24, and 25 being pivotally connected to the arms 19, 20 and 21 is capable of swinging movement, but this movement is limited by means of plates 30, 31, and 32 secured to the ends of the arms 19, 20, and 21 and having their ends turned over, as at 33 and 34, to form stops to limit the swing of the arms, the stops 33 being arranged so that on the upward movement of the elevator under the weight of the sheaf the arms 23, 24 and 25 are straightened out into line with the arms 19, 20 and 21. The spacing of the stops 34, however, is such that when the arms are carried over the top center into position for dumping the sheaf, the arms 23, 24 and 25 may fall forward a limited amount, as shown by the dotted lines in Fig. 1.

Loosely mounted on the shaft 10 towards one end is an arm 35 connected by a lever 36 to an arm 37 secured to the kicker shaft 4 the connection being arranged so that while the arm 37 makes a complete revolution the arm 35 only rocks an amount sufficient to raise the elevator arms from the normal position shown by the full lines in Fig. 1 to the position shown by the dotted lines and back again to the normal position. The arm 35 is provided with a notch 38 with which a squared pin 39 carried by shaft 10 is removably engaged, being held in engagement by means of a spring 40 disposed between a pin 41 passed through the pin 39 and a plate member 42 secured to the shaft, while it is capable of being withdrawn out of the notch by means of a connection 43 connected at one end to the pin while its opposite end is connected to a crank arm 44 secured to the end of the stooker shaft, indicated generally by the numeral 45, the pin

39 being prevented from reentering the notch 38 by a flange 46 on the arm 35 until it arrives at the correct reentering position.

5 The manner in which the device operates 5 may be briefly described, it being understood that when the elevator is out of operation the arms lie in the normal position shown by the full lines in Fig. 1. When the 10 binder commences cutting and the first sheaf is kicked on to the arms 5 and 6 it remains there until the next revolution of the 15 kicker shaft 4, but as soon as the kicker shaft commences to revolve to bring the next, or second, sheaf out of the binder, the first sheaf is immediately thrown into the basket of the stooker by the arms 19-23, 20-24, and 21-25, which are elevated by the operation of shaft 10, returning to their normal position before the second sheaf reaches the 20 arms 5 and 6, and this operation is repeated until a sufficient number of sheaves have been thrown into the basket. When the stooker mechanism is set in motion to deposit the stook on the ground, the pin 39 25 is automatically withdrawn from the notch 38 so that the elevator arms remain inoperative in their normal receiving position during the stook depositing operation. The 30 kicker shaft 4 continues to revolve so that one or more sheaves may be meanwhile deposited on the arms 5 and 6 and these are thrown into the basket when it returns to its normal horizontal sheaf-receiving position again since the pin 39 then reenters the notch 38 whereupon the elevator arms 35 resume their operation until the stooker basket is again filled.

What I claim as my invention is:—

1. The combination with a stooking machine and a binding machine, of a frame disposed between said machines on to which sheaves from the binding machine may be deposited, elevator arms arranged normally below said frame, a shaft to which said arms are secured, partial rotation of which elevates said arms to raise the sheaves and dump them into the stooking machine basket, an arm freely mounted on the end of said shaft having a flange concentric with the shaft provided with a notch, an arm secured to the binding machine kicker shaft, a connecting rod between said arms, a pin carried by said elevator arm shaft in 55 slideable engagement with said notch, and means for disengaging the pin out of the notch.
2. The combination with a stooking machine and a binding machine, of a frame disposed between said machines on to which sheaves from the binding machine may be deposited, elevator arms arranged normally

below said frame, a shaft to which said arms are secured, partial rotation of which elevates said arms to raise the sheaves and dump them into the stooking machine basket, an arm freely mounted on the end 65 of said shaft having a flange concentric with the shaft provided with a notch, an arm secured to the binding machine kicker shaft, a connecting rod between said arms, a pin carried by the elevator arm shaft in 70 slideable engagement with said notch, means for disengaging the pin out of the notch, and means for reengaging the pin in the notch after a predetermined interval of disengagement.

3. The combination with a stooking machine and a binding machine, of a frame disposed between said machines on to which sheaves from the binding machine may be deposited, a shaft mounted adjacent the 80 stooking machine for partial rotation, elevator arms arranged normally below said frame, each said arm comprising a main portion having one end secured to the said shaft and its opposite end provided with an 85 extension pivotally connected to it, said extension lying directly under the sheaf receiving portion of the frame, a bar carried by each extension disposed at right angles thereto and mechanism operated by the 90 binding machine kicker shaft for operating said elevator arm shaft to elevate said arms through a predetermined travel.

4. The combination with a stooking machine and a binding machine, of a frame disposed between said machines on to which sheaves from the binding machine may be deposited, a shaft mounted adjacent the 95 stooking machine for partial rotation, elevator arms arranged normally below said frame, each said arm comprising a main portion having one end secured to the said shaft and its opposite end provided with an 100 extension pivotally connected to it, said extension lying directly under the sheaf receiving portion of the frame, a bar rigidly carried by each extension and disposed at right angles thereto, mechanism operated by the binding machine kicker shaft for operating 105 said elevator arm shaft to elevate said arms through a predetermined travel, and stops carried by the main portion of each said arm whereby a predetermined amount of movement of each said extension about its pivotal connection in either direction is permitted.

Dated at Victoria, B. C., this 3rd day of September, 1921.

NORMAN HOWARD CAUFIELD.
